METHOD FOR ASSEMBLING HOGSHEADS

Harry Guthrie Bell, Paris, Ky., assignor to Gay-Bell Corporation, Paris, Ky., a corporation of Kentucky

Application July 18, 1955, Serial No. 522,456

1 Claim. (Cl. 1—84)

My invention resides in the provision of simplified apparatus for assembling hogsheads and specifically is directed to a method for fastening the intermediate hoops and end hoops-and-liners to the panels making up the hogshead.

I have found it advantageous to manufacture hogsheads by taking a plurality of panels made of plywood or the like, assembling them in side-by-side relationship, temporarily fastening end hoops-and-liners along the ends of the panels and intermediate hoops along the central portions thereof, permanently stapling the end hoops-and-liners and intermediate hoops to the panels and then sawing the panels transversely of the intermediate hoops and end hoops-and-liners whereby to form staves which are held by the intermediate hoops and end hoops-and-liners. The panels thus joined and sawed may then be wrapped into barrel shape and circular tops and bottoms supplied thus completing the hogshead.

It is an object of my invention to provide a method whereby in one pass half of the stapling job is completed while on the return pass the other half of such stapling job is accomplished.

These and other objects of my invention will become apparent to those skilled in the art during the course of the following description and with reference to the accompanying drawings, in which drawings like numerals are employed to designate like parts and in which:

Figure 1 is a top plan view, with parts broken away, of the apparatus of this invention.

Figure 2 is a side elevation, with parts broken away, of the apparatus of Figure 1.

Figure 3 is an enlarged section taken on the line 3—3 of Figure 2.

Figure 4 is a section taken on the line 4—4 of Figure 2.

Figure 5 is an enlarged fragmentary sectional view showing certain of the parts, and

Figure 6 is a plan view showing a plurality of panels joined by intermediate hoops and end hoops-and-liners by the apparatus of this invention, such figure also showing the lines along which the panels thus joined will be sawed to form the staves making up the side walls of the hogshead.

Referring now especially to Figures 1 and 2 it will be observed that apparatus which may be used in the method of my invention comprises a pair of elongated frame members 10 which are supported from legs 11 and braced by members 12, the frame members 10 being joined by cross members 13. The frame members 10 form tracks to receive the rollers 14 of a carriage which is formed of angle bars 15 joined together so as to form a rectangle. As seen in Figure 3 the rollers 14 have flanges 16 which engage the sides of the frame members 10 and serve to maintain the carriage 15 on the assembly. These rollers 14 may be mounted on short axles 17 which are welded or otherwise secured to the frame members forming the carriage.

Centrally of the frame members 10 I provide a pair of stapling devices located at either side of the apparatus.

2

Each of these devices comprises a head 18 and anvil 19. I have shown these stapling devices as being electrically actuated and to this end I provide leads 20 and a foot-operated switch 21 whereby both stapling devices are actuated simultaneously.

Fixed beneath the frame structure 10 is a member 22 which has a dovetail member 23 fixed thereto. Each of the stapling devices has a base member 24 with a dovetail slot to receive the member 23. A block 25 limits inward movement of the bases 24 of the stapling devices while members 26 limit the outward movement of such bases.

The stapling head 18 may have a pivoted connection as indicated at 27 with a member 28 extending from the main post 29 which is supported from the base 24. The anvil 19 may be secured to a lower member 30 also extending from the post 29. It will be understood that the details of the arrangement of the stapling devices do not constitute a limitation of the instant invention. These stapling devices may be purchased commercially and suffice it to say that upon actuation of the switch 21 the mechanism will drive a staple from the head 18, through the work and the legs of such staple will be clinched against the anvil.

In Figure 5 I have illustrated the positions taken by the head 18 and anvil 19 of the stapling devices during operation. It will be observed that a staple 31 is being driven through an end hoop-and-liner member 32 which is a U-shaped member fastened to the hogshead panels along the ends thereof. In driving the staple 31 through both legs of the U-shaped member 32 the head 18 and anvil 19 move towards the work and this is illustrated by the dotted line position of these members in Figure 5. This Figure 5 also shows the manner in which the hogshead panel 33 is carried by the carriage frame members 15.

As perhaps best seen in Figure 6 I prefer to make up a hogshead by taking three panels 33, placing them in side-by-side relationship, placing a pair of the U-shaped end hoop-and-liners 32 across both ends thereof, placing a pair of hoops 34 across the central portions of the panels, temporarily securing the members 32 and 34 and then fastening such members 32 and 34 to the panel members 33 in permanent fashion by use of the stapling devices and associated mechanism of this invention. The dot-dash lines 35 indicate the lines of cut which will eventually be given the various panels 33 in order to form staves which are held together by the hoops 34 and end hoops-and-liners 32.

I shall now describe the operation of my invention. It is assumed that a plurality of panels 33 have been placed together and the end hoops-and-liners 32 and intermediate hoops 34 have been put in position and perhaps there maintained by a tack or two. The rectangular carriage made up of the members 15 is of a size just sufficient to receive the assembly of panels 33. I have illustrated three such panels but it will be further understood that various numbers may be used so long as the carriage is adapted to receive such assembled panels as just described.

The operator will place the assembly of panels 33 in the carriage members 15 and at this point the various mechanisms will be in the position illustrated in full lines in Figure 1. The operator will push the carriage member 15 to the dotted line position shown in Figure 1. The staple heads will be positioned above the hoop and liner members 32 as illustrated in Figures 1 and 5. By actuating the foot pedal 21 in rapid succession as the carriage 15 is manually moved by the operator beneath the heads 18 a series of staples 31 is driven through the end hoops-and-liners 32 and the panels 33. Proper position of the heads 18 with respect to the end hoop-and-liners 32 is insured by the relationship between the abutment plates

26 and the staple bases 24. (It will be understood that mechanical means for moving the carriage and/or actuating the stapling heads may be employed as desired.)

Upon completing one pass of the carriage mechanism 15 whereby to move the mechanism from the full line position of Figure 1 to the dotted line position thereof, it will be apparent that the end hoop-and-liners 32 will be permanently fastened to the panel members 33 by a row of the staples 31. The operator will then move the stapling devices so as to bring the bases 24 into engagement with the block 25. This will move the heads 18 so as to bring them above the hoops 34. The operator will then return the carriage to its original position and while he does this he operates the foot pedal so as to drive a succession of staples through the intermediate hoops 34 into the panels 33 whereupon they will be clinched against the anvil 19. When the assembly of panels has thus been returned to its original position the intermediate hoops and the end hoops-and-liners will all be stapled to the panels permanently. The panels thus joined will be removed and another set placed within the carriage members 15 whereupon the operation just described may be repeated.

The reciprocable carriage mechanism 15 in combination with the shiftable stapling devices thus provides a basic mechanism by which I may securely fasten intermediate hoops and end hoops-and-liners 34 and 32 respectively to a plurality of panels 33 to form the basic hogshead structure preferred by me. It will be apparent to those skilled in the art that modifications may be made in the combination of structures illustrated without departing from the scope and spirit of this invention.

Also, while I have shown my invention as embodied in particular arrangements and structures I do not intend to be limited by such except insofar as they are specifically set forth in the subjoined claim.

Having thus described my invention, what I claim as new and what I desire to protect by United States Letters Patent is:

A method of securing end hoop-and-liners and intermediate hoops on hogshead panels which comprises the steps of placing a plurality of panels in flat side by side relationship, placing a first U-shaped end hoop-and-liner along the ends of said panels and a second U-shaped end hoop-and-liner along the opposite ends of said panels, placing a pair of intermediate hoops over said panels and between and parallel to said end hoop-and-liners, preliminarily securing said end hoop-and-liners and said hoops in assembled relation, moving said panels along a straight line path of travel beneath a pair of stapling devices, driving staples into two of the end hoop-and-liners and intermediate hoops, shifting said stapling devices, moving said panels back along said path of travel beneath said shifted pair of stapling devices, and driving staples into the remaining two of the end hoop-and-liners and intermediate hoops.
